The ornamental design for a pipe saddle, as shown and described.

DESCRIPTION

FIG. 1 is a perspective of a pipe saddle showing our new design;

FIG. 2 is a front elevational view of the pipe saddle;

FIG. 3 is a right elevational view of the pipe saddle;

FIG. 4 is a top plan view of the pipe saddle;

FIG. 5 is a rear elevational view of the pipe saddle;

FIG. 6 is a left elevational view of the pipe saddle; and,

FIG. 7 is a bottom plan view of the pipe saddle.
